UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 24, 1923. Serial No. 670,502.

My invention relates to railway traffic controlling apparatus, and particularly to apparatus of the type wherein governing mechanism on a train is controlled by energy in 5 the trackway. More particularly the present invention relates to the trackway portion of such apparatus.

I will describe one form of apparatus embodying my invention, and will then point 10 out the novel features thereof in claims.

In the accompanying drawings, Figs. 1 and 1^a, when placed end to end in the order named constitute a diagrammatic view showing a portion of one form of trackway apparatus embodying my invention. Fig. 2 15 is a view showing the remaining portion of the apparatus and also embodying my invention.

Similar reference characters refer to similar parts in each of the views.

Referring first to Figs. 1 and 1^a, the reference characters 1 and 1^a designate the track rails of a single track F, over which traffic moves in both directions, which track 25 is provided with a passing siding E. The stretch of track shown in the drawing is a unit complete in itself, so that if a plurality of these units are placed end to end they will form a system comprising a number of 30 stretches of single track separated by passing sidings E.

The stretch of track shown in the drawing is divided by insulated joints 2 in to four sections A—B, B—C, C—D and D—A. 35 Each section is provided with a track circuit comprising a source of current and a track relay located at one end of the section, and a second source of current and a second track relay located at the other end of 40 the section. Each source of current is a transformer designated by the reference character G with an exponent corresponding to the location, the secondary of which is constantly connected across the rails at the corresponding end of the section. Each track 45 relay is designated by the reference character T with an exponent corresponding to the location. Under normal conditions the primary of the transformer G at one end of 50 each section is energized and the primary of the transformer G at the other end of each section is de-energized, and both track relays for each section are connected with the rails of the section so that both of these re-

lays are energized. For present purposes I 55 will assume that these connections are constant for each section.

Traffic through the stretch of track shown in the drawing and moving from east to west is governed by three signals S', S³ and 60 S⁵, whereas traffic moving from west to east is governed by three signals S², S⁴ and S⁶. In the arrangement here shown, signals S⁵ and S⁶ are located at the entering ends respectively, of the track section D—A 65 containing the passing siding E, whereas signals S' and S² are located at the entering end, respectively, of the stretch of single track A—D. Signals S³ and S⁴ are intermediate signals in the stretch of single 70 track, and are staggered in location. As here shown, they are located at points B and C, respectively, although these specific locations are not essential.

The immediate control of each signal is 75 accomplished by a line relay designated by the reference character H with the same exponent as that applied to the associated signal. Each of these relays in the form here shown is of a three-position alternating current type comprising a line winding 76 and a local winding 77. In order to simplify the drawing, however, the local winding 77 is omitted from all the relays except relay H³. The local winding 77 is constantly 80 supplied with alternating current from an adjacent transformer J through a circuit which will be obvious from the drawing without further explanation. The line winding 76 is supplied with alternating current 85 of normal or reverse relative polarity, as will hereinafter appear.

Each signal is provided with a caution indication circuit and a proceed indication, which circuits are controlled by the associated relay H. Considering signal S³, for example, the caution circuit passes from the secondary of transformer J^c, through wires 4^B, and 6, contact 7 of relay H³, wire 8, operating mechanism of signal S³, wire 9, and wire 100 4^X to the secondary of transformer J^c. This circuit is closed when relay H³ is energized by current of either relative polarity. The proceed indication circuit for signal S³ is from transformer J^c, through wires 4^B and 6, contact 7 of track relay H³, wire 10, contact 11 of relay H³, wire 12, operating mechanism of signal S³, and wires 9 and 105

4^x to transformer J^c. This circuit is closed only when relay H³ is energized by current of normal relative polarity. It will be seen, therefore, that signal S³ indicates "caution" or "proceed" according as relay H³ is energized by current of reverse or normal relative polarity, and that this signal will indicate stop whenever relay H³ is de-energized.

It is understood that each of the remaining signals shown in the drawing is provided with circuits similar to those just explained in connection with the signal S³, but that such circuits are omitted from the drawing for the purpose of simplicity.

15 The circuit for the line winding 76 of line relay H³ is from the secondary of transformer K⁵, through wire 13, pole changer P⁵, wire 14, contact 15 of track relay T², wire 16, contact 17 of relay T⁷, wire 18, contact 19 of track relay T⁴, wire 20, back contact 21 of a relay R⁴, wire 22, contact 23 of track relay T³, wire 24, winding 76 of relay H³, wires 25 and 4^x, and common wires 26 and 27, wire 4^x at location A, wire 28, pole changer P⁵, and wire 29 to the secondary of transformer K⁵. The primary of transformer K⁵ is directly connected with the secondary of transformer J^A by wires 4^B and 4^x, and the primary of transformer J^A is connected with a transmission line 5 which is constantly supplied with alternating current from a generator 3. Pole changer P⁵ is operated by signal S⁵ in such manner that current of normal relative polarity is supplied to relay H³ when signal S⁵ indicates proceed or caution, but that current of reverse relative polarity is supplied to relay H³ when signal S⁵ indicates stop. Of course, relay H³ will be de-energized when any one 40 of the track relays T², T⁷, T⁴ and T³ is de-energized, that is, when there is a train anywhere between points A and C.

Line relay H⁴ of the other intermediate signal S⁴ is controlled in similar manner by 45 means of pole changer P⁶, contact 30 of track relay T¹, wire 31, contact 32 of track relay T⁸, contact 33 of track relay T⁸, back contact 34 of relay R³, and contact 35 of track relay T⁴. It follows that signal S⁴ will indicate stop when there is a train in section B—C or C—D.

The circuit for line relay H², controlling signal S², is from the secondary of transformer K⁴, through pole changer P⁴, wires 36 and 37, contact 38 of relay H⁴, wire 39, contact 40 of track relay T⁷, wire 41, contact 42 of track relay T², wire 43, line winding of relay H², wire 44, wire 4^x, common wire 27, wire 4^x at location B, and pole changer P⁴ to the secondary of transformer K⁴. It will be noted that this circuit includes a front contact of relay H⁴, so that in the absence of other means signal S² will indicate stop when there is a train in section A—B, B—C or C—D. The circuit for re-

lay H² is provided, however, with a branch around contact 38 of relay H⁴, which branch passes from wire 36, through wire 45, contact 46 of relay R⁴, and wire 47 to wire 39. When relay R⁴ is energized, it follows that 70 the circuit for relay H² will be closed, provided that track relays T² and T⁷ are energized.

Relay R⁴ is provided with a pick-up circuit which passes from the secondary of 75 transformer J^B, through wire 4^B, wire 65, back contact 64 of track relay T⁷, wire 63, back contact 62 of track relay T⁴, wire 61, circuit controller 60 operated by signal S⁴, wire 49, winding of relay R⁴, and wires 58 80 and 4^x to the secondary of transformer J^B. This circuit is closed only when track relays T⁷ and T⁴ are both de-energized and signal S⁴ indicates either proceed or caution, and so it follows that relay R⁴ can be picked up 85 only when an eastbound train passes signal S⁴. The relay R⁴ is provided with a stick circuit which passes from secondary of transformer J^B, through wires 4^B and 70, back contact 69 of relay H⁴, wire 68, contact 67 of relay R⁴, wire 66, winding of relay R⁴ and wires 58 and 4^x to the secondary of transformer J^B. It follows that when relay R⁴ becomes energized, it remains energized 90 as long as relay H⁴ is de-energized.

Line relay H¹ for signal S¹ is controlled in the same manner as relay H², that is, the circuit for relay H¹ includes pole changer P³, contact 48 of relay H³, contact 49 of track relay T⁸, wire 50, and contact 51 of track relay T¹. This circuit is provided with a branch around contact 48 of relay H³, which branch includes contact 52 of relay R³. Relay R³ is provided with a pick-up circuit controlled by circuit controller 71 on signal S³ and back contacts 72 and 73 of track relays T³ and T⁸, respectively, so that relay R³ can be energized only when a westbound train passes signal S³. Relay R³ then 100 remains energized as long as line relay H³ is de-energized.

Line relay H⁶ for signal S⁶ is controlled by pole changer P² of signal S², contact 52 of track relay T², contact 53 of track relay T⁵, and contact 54 of track relay T⁶. It 115 follows that signal S⁶ indicates stop whenever there is a train in section D—A or A—B, and that when these sections are both unoccupied the relative polarity of the current supplied to the relay H⁶ is determined by the position of signal S².

Relay H⁵ for signal S⁵ is controlled in the same manner as relay H⁶, that is, it is controlled by pole changer P¹, contact 55 of track relay T¹, contact 56 of track relay 120 76 and contact 57 of track relay T⁵.

The signaling system which has thus far been described is what is termed the "absolute permissive" type, and operates in accordance with principles which are well un- 125 130

derstood. It follows that no further explanation of the operation is required at this point.

The trackway apparatus illustrated in the accompanying drawings is intended for cooperation with train-carried apparatus which requires the supply of train governing energy from the trackway to permit the train to proceed. This energy comprises track circuit current connected across the rails ahead of the train and line current supplied between two points on at least one rail. Considering specifically the track circuit current, it is obvious that in so far as the apparatus thus far described is concerned, a train moving toward the west would receive track circuit current from the transformer G located at the left hand end of each section except C—D, but that a train moving toward the east would not receive track circuit current in any section except C—D because the transformers G at the right hand ends of the remaining sections are normally disconnected from sources of current. For this reason the system includes auxiliary relays L and repeating relays M which serve to reverse the track circuits when necessary. Considering track section B—C specifically, relay L⁴ is provided with a circuit which passes from the secondary of transformer J^B, through wires 4^B and 78, back contact 79 of track relay T⁴, wire 80, contact 81 of stick relay R⁴, wire 82, winding of relay L⁴ and wires 83 and 4^X to the secondary of transformer J^B. It follows that relay L⁴ can be energized only when an eastbound train enters section B—C, because this is the only time that relay R⁴ is energized, and it also follows that relay L⁴ will become de-energized, as soon as such train passes out of section B—C because back contact 79 of track relay T⁴ becomes opened at such time. While relay L⁴ is energized, relay M⁴ is energized by virtue of a circuit which passes from the secondary of transformer J^B, through wire 84, contact 85 of relay L⁴, wire 86, back point of contact 35 of track relay T⁴, wire 87, back contact 34 of relay R³, wire 88, back point of contact 33 of track relay T³, wire 89, winding of relay M⁴, and wires 90, 4^X and 26 to the secondary of transformer J^B.

As long as relay L⁴ is de-energized, the primary of transformer G⁴ is connected with the secondary of transformer J^B, through wire 84, contact 91, wire 92, primary of transformer G⁴, and wires 93 and 4^X. When relay L⁴ becomes energized, this circuit is opened. As long as relay M⁴ is de-energized, track relay T³ is connected across the rails of section B—C through wire 94, winding of relay T³, wire 95, back contact 96 of relay M⁴ and wire 97. When relay M⁴ becomes energized, track relay T³ is disconnected from the rails and the primary of

transformer G³ is connected with the secondary of transformer J^C, through wire 101, contact 98, wire 100, and wire 4^X. It follows, therefore, that when an eastbound train enters section B—C, the closing of relays L⁴ and M⁴ operates to disconnect the source of current from the rails at the left hand end of the section, to disconnect track relay T³ from the rails at the right hand end, and to connect the source of current at the right hand end with the rails of the section. The train, therefore, receives track circuit current from a source ahead of the train as long as the train is in the section. When the train passes out of section B—C, track relay T⁴ becomes energized, thereby de-energizing relays R⁴ and R⁵, whereupon the track circuit is restored to its normal condition.

It will be noted that relay L⁴, which controls the reversal of the track circuit of section B—C, remains energized only as long as a train is in the section, so that this relay cannot be used to remove line relay H⁴ from control of line relay H². For this reason I have provided the two relays R⁴ and L⁴, the former of which controls signal S² during eastbound train movements, and the latter of which controls the reversal of the track circuit for section B—C.

In section A—B the reversal of the track circuit is accomplished by relays L² and M². Relay L² is controlled by back contact 102 of track relay T² and circuit controller 103 on signal S², so that this relay can be energized only when an eastbound train passes signal S². A stick circuit for relay L² includes contact 104 of relay L² and back contact 102 of track relay T², so that relay L² becomes de-energized as soon as an eastbound train passes point B.

Relays L⁶ and M⁶ for section D—A, and relays L' and M' for section C—D are controlled in the same manner as the relays L² and M² for section A—B. It should be noted, however, that in section C—D the transformer G' at the right hand end of the section is normally connected with its source of current, and that when a westbound train enters the section relays L' and M' become energized and function to disconnect this transformer from its source of current and to connect transformer G⁸ at the left hand end of the section with its source of current.

Referring now to Fig. 2, I have here shown the circuits for supplying local current of the train governing energy, and in order to simplify the drawing I have in this view omitted the circuits shown in Figs. 1 and 1^a for controlling the several relays.

It is understood that the train-carried governing apparatus is so arranged that when the train receives local current of normal relative polarity and also track circuit

current, a proceed indication is given aboard the train; when the train receives local current of reverse relative polarity and also track circuit current, a caution indication is given aboard the train; and when the supply of either local current or track circuit current or both is discontinued, a stop indication is given aboard the train.

In order to explain the apparatus shown in Fig. 2, I will assume that a westbound train enters section B—C. Relay R³ is then closed, so that the secondary of transformer N⁴ is connected with the rails through wire 105, resistance 114, the two track rails of section B—C in multiple, resistance 115 at the east end of the section, wires 106 and 107, contact 108 of relay R³, wire 109, back contact 110 of relay M⁴, wire 111, back contact 112 of relay L⁴, and wire 113 to the secondary of transformer N⁴. The primary circuit for transformer N⁴ is from the secondary of transformer J^A, through wire 4^P, contact 116 of relay H⁵, wire 117, contact 118 of track relay T⁷, wire 119, primary winding of transformer N⁴, wire 120, contact 121 of relay H⁵, and wire 4^X to the secondary of transformer J^A. The contacts of relay H⁵ constitute a pole changer in this circuit, so that current of normal or reverse relative polarity is supplied to transformer N⁴ according as relay H⁵ is energized or de-energized. It follows that if signal S⁵ indicates proceed or caution, so that signal S³ indicates proceed, the train will be supplied with local current of normal relative polarity and also with track circuit current, so that a proceed indication will be given on the train. If, however, signal S⁵ is at stop, relay H⁵ will be de-energized, so that local current of reverse relative polarity will be supplied to the train, and, consequently, a caution indication will be given on the train corresponding to the caution indication given by the wayside signal S³.

As the train enters section A—B it will receive local current from the secondary of transformer N², the primary of which is supplied with current of normal or reverse relative polarity through the contacts 116 and 121 of relay H⁵. Assuming that signal S⁵ is in the proceed or caution position, that is, assuming that relay H⁵ is energized, the secondary circuit for transformer N² is through wire 122, front contact 123 of relay H⁵, wires 124 and 125, resistance 114, the rails of section A—B, resistance 115, wires 126 and 127, back point of contact 128 of relay M², wire 129, back point of contact 130 of relay L², and wire 131 to the secondary of transformer N². Local current of normal relative polarity will then be supplied to the rails throughout the length of section A—B, so that a proceed indication will be given on the train throughout this section. If, however, signal S⁵ indicates stop, that is, if re-

lay H⁵ is de-energized, current of reverse relative polarity will be supplied to the primary of transformer N², and the secondary circuit for this transformer will be through wire 122, back point of contact 123 of relay H⁵, wire 132, resistance 114^a, the rails of section A—B to resistance 115, and thence, as before, to the secondary of transformer N². Under this condition local current of reverse relative polarity will be supplied to the train from resistance 115 to resistance 114^a, but no local current will be supplied between resistances 114^a and 114. Consequently, the train will receive a caution indication as far as 114^a, and a stop indication from that point to resistance 114.

While the westbound train is passing through section D—A, it will receive local current from transformer N⁶, the primary circuit of which is controlled by relay H⁷. When signal S' indicates proceed or caution, local current is supplied to section D—A throughout the length of the section, the circuit including back contact 138 of relay M⁶ and back contact 137 of relay L⁶, but when signal S' indicates stop, local current of reverse relative polarity will be supplied from resistance 115 to resistance 114^a and no local current will be supplied from the latter point to resistance 114.

While the westbound train is passing from point D to point C, local current will be supplied from transformer N⁸, the secondary circuit of which is controlled by contact 133 of relay H³ and also by the front points of contacts 135 of relay M¹ and 134 of relay L¹, it being remembered that relays L¹ and M¹ are energized while the westbound train is in section C—D.

Assuming now that an eastbound train enters section D—A, the supply of local current is derived from transformer N⁵, the secondary circuit of which is controlled by contact 136 of relay H². Relays L⁶ and M⁶ are both energized, so that the local circuit includes the front points of contact 137 of relay L⁶ and 138 of relay M⁶.

Similarly, in section A—B, the supply of local current is furnished by transformer N⁷, through front points of contacts 130 of relay L² and 128 of relay M². In section B—C, local current is supplied by transformer N⁸, the secondary circuit for which includes the front point of contact 110 of relay M⁴ and front point of contact 112 of relay L⁴, both of which relays are energized while the train is in this section. The primary of transformer N⁸ is supplied with current from transformer J^D, and this primary circuit is controlled by relay H⁶ and also by contact 139 of track relay T⁸. The primary circuit for transformer N⁸ is similar in all respects to the primary circuit hereinbefore traced for transformer N⁴. In section C—D the local current is supplied by transformer

N' through back points of contacts 135 of relay M' and 134 of relay L', both of which relays remain de-energized.

One important feature of the apparatus shown in Fig. 2 is the control of transformer N⁴ by pole changing contacts in relay H⁵, and the similar control of transformer N⁸ by pole changing contacts in relay H⁶. By virtue of this control I am enabled to govern the indications given aboard a train in section B—C in accordance with indications given by wayside signals S³ and S⁴.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track over which traffic moves in both directions including a section B—C, a track relay for said section, a source of track circuit current at the west end of the section normally connected with the rails and a source of track circuit current at the east end of the section normally disconnected from the rails of the section, an eastbound signal located at the west end of said section, a line relay for controlling said signal and for normally also controlling a signal in the rear, means for controlling said line relay by the track relay for said section and by a train up to a certain point to the east of said section, a normally de-energized stick relay at the west end of said section arranged when energized to remove said line relay from control of said signal in the rear, means for energizing said stick relay when an eastbound train enters the section and for subsequently keeping it energized until said line relay becomes energized, an auxiliary relay at the west end of said section controlled by a front contact of said stick relay and a back contact of a track relay for said section whereby said auxiliary relay becomes energized only when an eastbound train enters the section and becomes de-energized as soon as such train leaves the section, a repeater relay at the east end of said section and controlled by said auxiliary relay, and means operating when said auxiliary and repeater relays are closed to disconnect the source of track circuit current at the west end from the rails of the section and to connect the source at the east end with the rails of the section.

2. In combination, a stretch of railway track over which traffic moves in both directions and including a section B—C, a stick relay and an auxiliary relay for said section, means for operating said stick relay when a train moving in one direction enters

the section and for keeping it in operated condition until the train passes a given point beyond said section, means for operating said auxiliary relay only when a train moving in the same direction occupies said section, signaling means controlled by said stick relay, and a reversible track circuit for said section controlled by said auxiliary relay.

3. In combination, a stretch of railway track over which traffic moves in both directions and including a section B—C, a stick relay and an auxiliary relay for said section, means for operating said stick relay when a train moving in one direction enters the section and for keeping it in operated condition until the train passes a given point beyond said section, means for operating said auxiliary relay only when a train moving in the same direction occupies said section, a signal for said section, a line relay controlling said signal and normally also controlling a signal in the rear, means effective when said stick relay is in operated condition to remove said line relay from control of the signal in the rear, and a reversible track circuit for said section controlled by said auxiliary relay.

4. In combination, a stretch of railway track over which traffic moves in both directions and including a section B—C, a stick relay and an auxiliary relay for said section, means for operating said stick relay when a train moving in one direction enters the section and for keeping it in operated condition until the train passes a given point beyond said section, means for operating said auxiliary relay only when a train moving in the same direction occupies said section, signaling means controlled by said stick relay, a source of track circuit current at each end of said section the first source being normally connected with the track rails and the second source being normally disconnected from the rails, and means effective when said auxiliary relay is in operated condition for disconnecting the first source from the rails and connecting the second source with the rails of the section.

5. In combination, a stretch of railway track over which traffic moves in both directions and including a section B—C, a stick relay and an auxiliary relay for said section, means for operating said stick relay when a train moving in one direction enters the section and for keeping it in operated condition until the train passes a given point beyond said section, means for operating said auxiliary relay only when a train moving in the same direction occupies said section, a signal for said section, a line relay controlling said signal and normally also controlling a signal in the rear, means effective when said stick relay is in operated condition to remove said line relay from

- control of the signal in the rear, a source of track circuit current at each end of said section the first source being normally connected with the track rails and the second source being normally disconnected from the rails, and means effective when said auxiliary relay is in operated condition for disconnecting the first source from the rails and connecting the second source with the rails of the section.
6. In combination, a section of railway track, a transformer for supplying local train controlling current to said section, a relay controlled by traffic conditions in advance of said section and having a contact included in the secondary circuit of said transformer for connecting said secondary with at least one rail throughout the section or through a portion only of the section, and other contacts of said relay included in the primary circuit of said transformer for varying the instantaneous relative polarity of the current supplied to said section.
7. In combination, a stretch of railway track comprising a rear and a forward section, a track circuit for said forward section, a relay controlled by traffic conditions in advance of said forward section, a transformer for supplying local train controlling current to said rear section, a primary circuit for said transformer controlled by said track circuit, and a pole changer included in said primary circuit and comprising contacts of said relay.
8. In combination, a stretch of railway track comprising a rear and a forward section, a track circuit for said forward section, a transformer for supplying local train controlling current to said rear section, a primary circuit for said transformer controlled by said track circuit, and a relay controlled by traffic conditions in advance of said forward section and operating to reverse the instantaneous relative polarity of the current supplied to the primary of said transformer.
9. In combination, a stretch of railway track over which traffic moves in both directions, three signals S' , S^2 and S^5 for governing traffic in one direction through said stretch, three signals S^2 , S^4 and S^6 for governing traffic in the other direction through
- said stretch, the intermediate signals being staggered and having a track section B—C between them, a transformer for supplying local train controlling current to said section B—C, a primary circuit for said transformer controlled by traffic conditions between signals S^2 and S^4 , and a line relay functioning to control signal S^5 and to also reverse the instantaneous relative polarity of the current in the primary circuit of said transformer.
10. In combination, a stretch of railway track over which traffic moves in both directions and including a section B—C, a stick relay and an auxiliary relay for said section, means for operating said stick relay when a train moving in one direction enters the section and for keeping it in operated condition until the train passes a given point beyond said section, means for operating said auxiliary relay only when a train moving in the opposite direction occupies said section, signalling means controlled by said stick relay, and means controlled by said auxiliary relay for supplying local current to said section.
11. In combination, a stretch of railway track over which traffic moves in both directions and including a section B—C, a stick relay and an auxiliary relay for said section, means for operating said stick relay when a train moving in one direction enters the section and for keeping it in operated condition until the train passes a given point beyond said section, means for operating said auxiliary relay only when a train moving in the opposite direction occupies said section, a repeater relay operated only when said auxiliary relay is operated and said section is occupied, signalling means controlled by said stick relay, a local circuit for governing traffic in one direction through said section and closed only when said stick relay is operated and said auxiliary and repeater relays are normal, and a second local circuit for governing traffic in the other direction through said section and closed only when said auxiliary and repeater relays are operated.

In testimony whereof I affix my signature.

RONALD A. McCANN.
